(57) **CLAIM**

The ornamental design for a portable platform for an imaging device, as shown and described.

DESCRIPTION

FIG. 1 is a right side perspective view of a portable platform for an imaging device showing my new design;

FIG. 2 is a front perspective view thereof;

FIG. 3 is a front elevational view thereof;

FIG. 4 is a right side elevational view thereof, the undisclosed left side view being a mirror image;

FIG. 5 is a rear elevational view thereof;

FIG. 6 is a bottom plan view thereof; and,

FIG. 7 is a top plan view thereof.

The broken lines shown do not form part of the claimed design.
